US0D1090849S

(12) **United States Design Patent** (10) **Patent No.:** **US D1,090,849 S**
(45) **Date of Patent:** **** Aug. 26, 2025**

(54) **HEARING AID**

(71) Applicant: **SOUNDUCT**, Strasbourg (FR)

(72) Inventors: **Jean-Philippe Marie De Chastenay**, Paris (FR); **Gautier Coulon**, Saint-Dié (FR)

(73) Assignee: **SOUNDUCT**, Strasbourg (FR)

(**) Term: **15 Years**

(21) Appl. No.: **29/937,445**

(22) Filed: **Apr. 15, 2024**

Related U.S. Application Data

(62) Division of application No. 35/517,904, filed on Jun. 22, 2023 (U.S. filing date under 35 U.S.C. 384), and having an international filing date of Jun. 22, 2023.
